REFRIGERATING APPARATUS FOR VENDING MACHINES

Olaf C. Olsen, Kansas City, Mo., assignor to C. Earl Hovey, trustee, Kansas City, Mo.

Application April 2, 1941, Serial No. 386,489

8 Claims. (Cl. 62—102)

This invention relates to vending machines and particularly refrigerating apparatus for such equipment, and the primary object is to provide compact, portable, unitary and efficient parts that may be installed in conventional vending machine cases without altering the same and in a manner as to effectively maintain the temperature of the bottles being vended at a predetermined temperature.

One of the important objects of the instant invention is to provide refrigerating apparatus for vending machines, which comprises a uniquely constructed coil that is disposed within a specially formed duct, wherein a fan is mounted, whereby currents of air are moved across the refrigerating coil and thence outwardly from one end of the said duct, the form of which is such as to direct the cold air around the necks of the bottles in the vending machine.

Another aim of this invention is to provide refrigerating apparatus for bottle vending machines having a refrigerating coil formed to present a number of straight stretches upon which is secured longitudinal fins serving to divide the air duct within which the refrigerating coil is housed, into a number of air passageways extending below the bottles or articles to be cooled, and merging with a reduced portion of the air duct, wherein is mounted a fan for the purpose of establishing positive movement of air from one end of the air duct to the other.

A further aim of this invention includes the use of specially designed fins that are mounted upon straight stretches of a refrigerating coil in such fashion as to establish relatively large areas of contacting metal whereby heat exchange is effectively established without retarding the flow of air and without establishing voids or pockets behind or adjacent to parts of the refrigerating coil.

Other objects of the invention include the specific details of construction and the arrangement of parts, as will become clear during the course of the following specification, referring to the accompanying drawings, wherein:

Fig. 1 is a top plan view of a bottle vending machine having refrigerating apparatus therein, made in accordance with the present invention.

Fig. 2 is a side elevational view of the same with a portion of the side wall broken away to reveal in elevation, parts of the refrigerating apparatus.

Fig. 3 is a horizontal cross sectional view through the vending machine with the bottle

rack removed therefrom and illustrating in elevation, the refrigerating apparatus therein.

Fig. 4 is a side elevational view of the unitary refrigerating apparatus entirely removed from association with the vending machine case.

Fig. 5 is an enlarged fragmentary sectional view through a portion of the air duct having the refrigerating coils therein, taken on line V—V of Fig. 3.

Fig. 6 is a fragmentary sectional view through a portion of the air duct taken on line VI—VI of Fig. 5; and

Fig. 7 is a sectional view through a portion of the air duct taken on line VII—VII of Fig. 6.

Vending machines of the character with which the refrigerating apparatus embodying this invention is particularly adapted for use comprises in the main, an insulated case 10 having a cover 12, a delivery door 14, and coin actuated mechanism diagrammatically illustrated at 16.

Bottles 18 are contained in annular paths below delivery door 14 and held in a rack 20 that may be suspended by brackets 22, or otherwise mounted where the bottles 18 are held with the crown caps 24 thereof a short distance below the bottom of cover 12.

Distributors of soft drinks, for example, have located a large number of vending machine cases of the character just referred to and illustrated in Figs. 1, 2 and 3, and in many instances the medium for cooling bottles 18, is water-ice. Mechanical refrigerating apparatus, to be successful insofar as installation and operation is concerned, must include unitary elements that may be moved to place within case 10 without structurally altering the latter.

The refrigerating coils must be disposed within a duct in a manner as to effect the greatest amount of heat exchange and movement of the air within case 10 should be in paths causing impingement upon bottles 18 that are within rack 20 and ready for removal from case 10.

It is further commercially desirable to store a certain number of bottles within the case so that when rack 20 is emptied by customers, a new supply of bottles 18 may be placed therein that are relatively close to the desired temperature. Pre-cooling therefore, is an element and if the air passing across the refrigerating coils and thence against the bottles being dispensed, is not directed in accordance with this invention, it is quite likely that bottles being pre-cooled or stored and made ready for introduction into rack 20, will greatly affect the efficiency of the machine.

The illustrated embodiment of refrigerating apparatus capable of meeting the desires of a vending machine operator, comprises a refrigerating coil broadly indicated by the numeral 26. This coil includes a number of relatively long, straight stretches 28 joined at their ends and return bends 30 to present a continuous coil conduit for the refrigerant which is supplied through branches 32 and 34 leading to and from respectively the compressor and associated conventional parts, not here shown.

The relatively flat side portion 36 of air duct 38 is preferably built up, as illustrated in Figs. 5, 6 and 7. One end of this portion 36 of duct 38 is open and in communication with the compartment formed within insulated case 10. The remaining part of duct 38 is extended upwardly and transversely across the top of portion 36 at one end thereof to terminate in a nozzle portion 40, having a number of slots 42 in the wall 44 thereof, which faces inwardly over portion 36. This nozzle 40 is slightly arcuate to direct currents of air across bottles 18 on a level at the reduced necks thereof. The direction of movement of the air currents will be as illustrated in Fig. 2.

A fan 46 driven by motor 48 is within duct 38 at the point of juncture between nozzle portion 40 and flat portion 36 thereof. Obviously, fan 48 may be continuously driven or caused to intermittently run by the employment of a thermostat control, not here shown, but which is of conventional character and forms no part of this invention.

Straight stretches 28 of coil 26 lie in parallelism with the path of movement of air through portion 36 of the duct. These straight stretches 28 are spaced apart and each is provided with a longitudinally extending fin, normally vertical and in a plane intersecting the longitudinal axis of the stretch of coil 26. Each fin 50 is forced onto straight stretch 28 after laterally pressed, staggered loops 52 are formed therein. These loops in their aggregate engage an appreciable amount of the outside face of stretches 28 and heat exchange is facilitated because each fin 50 is bent as at 54 to form a part of the upper and lower walls of portion 36 of air duct 38. Thus, each fin 50 is U-shaped in transverse cross section; the legs 56 of each U-shaped fin are a component part of the side walls of duct portion 36 and the bight of each U-shaped fin 50 is in metal-to-metal contact with part 28 of the refrigerating coil. Air passages 58 are created through such construction and all of said passages 58 merge at the end of duct portion 36 with nozzle portion 40 of duct 38. The movement of air through passages 58 is not retarded by any part of fins 50 but heat exchange occurs on all sides of the stream of air.

The area of duct portion 36 is substantially the same as the area of bottle rack 20 but slightly less than the area of the bottom of case 10. Storage space for a reserve supply of bottles 18 is thereby established and this storage space is on one side of the paths of movement of the air serving to cool bottles 18 in rack 20. The reserve supply of bottles will be cooled without affecting the temperature of bottles 18 that are in place for removal through delivery door 14.

The form of nozzle 40 is such as to direct the air against bottles 18 that are ready for use. The open intake end of duct 38 is spaced from the inner face of case 10 and while air is drawn into duct 38 from the compartment formed in case 10

without regard to any particular portion of the space it is ejected from duct 38 through slots 42 only after the temperature has been lowered in passageways 58 to a degree where bottles 18 in rack 20 will be affected in a desired manner, i. e., to lower the temperature.

From the foregoing it will be observed that the parts illustrated in Fig. 4 and constituting all that is necessary to introduce to case 10 may be transported and installed as a unit. The arcuate face of nozzle portion 40 of duct 38 is substantially concentric with the paths in which bottles 18 are disposed and the slots 42 are higher and at one end of the unit, while the intake open end of portion 36 of duct 38 is relatively low and at the opposite end of the unit. The bottles 18 are disposed between slots 42 and the intake end of duct 38 and therefore, the contents thereof must respond to the action of air currents travelling as indicated by the arrows in Fig. 2.

Having thus described the invention, what is claimed as new and desired to be secured by Letters Patent is:

1. Refrigerating apparatus for bottle vending machines comprising an insulated case; a rack for holding the bottles vertically; a coil for a refrigerant disposed below the rack; a duct housing the coil, extending to a point above the rack and forming a floor for bottles in the rack; and a fan in the duct for moving air through the duct, across the coil and against the bottles above the rack.

2. Refrigerating apparatus for bottle vending machines comprising an insulated case; a rack for holding the bottles vertically; a coil for a refrigerant disposed below the rack; a duct housing the coil, extending to a point above the rack and forming a floor for bottles in the rack; and a fan in the duct for moving air through the duct across the coil and against the bottles above the rack, said coil having fins thereon disposed parallel to the path of travel through the duct and in direct contact with the floor.

3. Refrigerating apparatus for bottle vending machines comprising an insulated case; a rack for holding the bottles vertically; a coil for a refrigerant disposed below the rack; a duct housing the coil, extending to a point above the rack and forming a floor for bottles in the rack; and a fan in the duct for moving air through the duct, across the coil and against the bottles above the rack, said coil having fins thereon disposed parallel to the path of travel through the duct and in direct contact with the floor, said fins extending the full width of the duct whereby to form a plurality of air passages therein.

4. In refrigerating apparatus of the character described, a unitary structure bodily movable to and from the operative position comprising an air duct having a relatively flat, box-like portion; a fan in the duct for moving air through the duct; a refrigerating coil provided with a number of straight stretches in the box-like portion disposed parallel to each other and to the path of travel of air in the said portion; and fins on the straight stretches of the coil parallel thereto and extending to the opposite walls of the duct to divide the same into a series of air passageways.

5. In refrigerating apparatus of the character described, a unitary structure bodily movable to and from the operative position comprising an air duct having a relatively flat, horizontal box-like portion; a fan in the duct for moving air through the duct; a refrigerating coil provided

with a number of straight stretches in the box-like portion disposed parallel to each other and to the path of travel of air in the said portion; and fins on the straight stretches of the coil extending to the opposite walls of the duct to divide the same into a series of air passageways, said duct having a vertical nozzle portion provided with a port disposed for directing air through paths of travel across the box-like portion in spaced relation thereto.

6. In refrigerating apparatus of the character described, a refrigerating coil having a number of straight stretches; a duct housing the coil and forming a support for the articles being refrigerated; a fan in the duct for moving air therethrough; and fins on the said straight stretches of the coil disposed in parallel relation with the straight stretches thereof and having their outermost edges in connection with opposite walls of the duct to form passageways in the duct along each side of each straight stretch of the coil.

7. In refrigerating apparatus of the character described, a refrigerating coil having a number

of straight stretches; a duct housing the coil; a fan in the duct for moving air therethrough; and fins on the said straight stretches of the duct disposed in parallel relation with the straight stretches and having their outermost edges in connection with opposite walls of the duct to form passageways in the duct along each side of each straight stretch of the coil, each fin having loops formed thereon to embrace the respective stretch of the coil.

8. In refrigerating apparatus of the character described, a refrigerating coil having a number of straight stretches; a duct housing the coil; a fan in the duct for moving air therethrough; and fins on the said straight stretches of the duct disposed in parallel relation and having their outermost edges in connection with opposite walls of the duct to form passageways in the duct along each side of each straight stretch of the coil, each fin extending outwardly from the respective stretch of the coil on a plane intersecting and parallel to the longitudinal axis of the stretch.
